TOBACCO STEMMING

Wilhelm B. Bronander, Montclair, N. J., assignor
to International Cigar Machinery Company, a
corporation of New Jersey

Application November 5, 1935, Serial No. 48,353

5 Claims. (Cl. 131—57)

This invention relates to tobacco stemming and has for its general object cutting the blade portions of tobacco leaves from the stem in an improved manner.

5 The invention is particularly designed for, although not limited to the stemming of cigar filler and wrapper tobacco wherein the tobacco is relatively valuable and wherein also it is desirable to retain the strips in flat uncrumpled condition. 10 In stemming or stripping machines for this purpose, it has hitherto been the common practice to feed the stem of the leaf between two flanges and a double-edged knife placed between and cooperating with the flanges so that the tobacco leaf is sheared from the stem. While machines of this type have been widely used with satisfactory results, they leave a portion of the leaf blade along the stem, particularly toward the small end of the stem, since the knives are 15 a fixed distance apart and do not follow the taper of the stem. Also in such mechanisms it is important that the leaf be carefully guided in order to prevent the knives from cutting across the stems, which is also likely to occur when the stems are crooked. These machines do not lend 20 themselves to automatic feeding of tobacco leaves because of the necessity of careful guiding referred to above.

The principal objects, therefore, of the present invention are to provide an improved stemming unit which avoids some of the above difficulties and limitations, and has peculiar advantages of its own such for instance as close stripping and a tendency to be selfguiding on the tobacco stem.

35 With these objects the invention contemplates the provision of flexible endless cutting or sawing members designed to hug and follow a stem surface. To secure this result, it is one of the 40 objects of the invention to provide for yieldingly urging the stemming elements into contact with the stem. In so doing, the danger arises that the cutting surfaces pressed close to the stem may cut into or cross the stem and it is, therefore, 45 an important object of the invention to minimize this possibility by rounding or beveling the face or edge portion of the stemming element adjacent the stem surface. This also has an advantage in that it tends to guide the stem between the cutting or sawing elements despite 50 crookedness of the stem and the lack of hand guiding. Indeed, it is contemplated that with the present invention the stem, once the butt end is passed between the stripping elements, 55 may be pulled through the same without need

of manual guiding of the trailing portion of the leaf and stem. Thus, the present stemming unit lends itself to mechanical feeding and makes possible a decrease in the attention required by the operator.

A feature of the invention lies in the use of a thin saw toothed cutting edge which has been found particularly efficient in sawing between the stem and the blade portion of the leaf. Since the cutting element is not intended to be rigid, 10 it may be made quite narrow, both transversely of the axis of the stem and also lengthwise of the stem axis, particularly as to the portion engaging the stem. This makes it possible for crooked stems to weave their way through the 15 space between the cutting elements for close stemming, regardless of the contours of the stem and makes possible clean stemming of a type of stem which offers a great deal of difficulty with existing stripping machines.

20 Another object of the invention is to avoid in this type of stripper a shearing action and thus eliminate ledger plates and similar structure requiring a fixed distance between the cuts on each side of the stem and detracting from its flexibility in fitting varying widths of stems.

Another object is to provide a novel method of stemming wherein the blade portions of the tobacco leaf are sawed apart from the stem along the surface of the stem.

30 With the object of showing a selected embodiment of the invention, the invention is shown in combination with a booking drum, but it should be understood that the stripping unit referred to is useable in a wide variety of machines and 35 applications.

With these and other objects not specifically mentioned in view of the invention consists in certain steps and constructions which will be hereinafter fully described and then specifically 40 pointed out in the claims hereunto appended.

In the accompanying drawing, which forms a part of this specification and in which like characters of reference indicate the same or like parts,

45 Fig. 1 is a front elevation, partly broken away, showing the improved stemming unit applied to a tobacco booking machine;

Fig. 2 is a side elevation of the machine illustrated in Fig. 1 on line 2—2 thereof; and

Fig. 3 is an enlarged detail plan view, partly in section, showing the stripping elements.

The method and apparatus herein referred to may be widely varied in construction within the scope of the claims, for the specific methods and 55

constructions selected to illustrate the invention are but certain of many possible embodiments of the same. The invention, therefore, is not to be restricted to the details illustrated and described, 5 nor to the particular embodiments chosen as illustrative of the invention.

Referring to Figs. 1 and 2 of the drawing, the stemming unit referred to is shown for purposes of illustration in combination with a booking 10 mechanism, the side frames 10 of which are held together by tie rods 11 and carry the drum shaft 12, drive shaft 13, roller shafts 14, 15, and 16, screw studs 17, and fulcrum shafts 18 and 19. On shaft 16, which has a flanged roller 20 and 15 is swingable by a handle 21, are fixed arms 22 carrying between them a shaft 23 on which the rollers 24 for the upper loop ends are mounted, and a rod 25 against which the loop belts rest in their open position when the handle 21 has been 20 swung in the direction of the arrow shown in Fig. 2. On the studs 17 are swingable end-brackets 26 which are joined by the lead-in guide plate 27 and carry a shaft 28 which has rollers 29 for the lower loop-ends. The brackets 26 are 25 swingable by means of crank arms 30 connected by links 31 to arms 32 on shaft 18, one of the latter arms having a handle 33 for this purpose. By turning the handles 21 and 33 in the directions of the arrows, the ends of the loops 34 are raised 30 off the drums 35, thereby permitting periodic removal of the leaf books B from the machine.

The booking belts 34 which surround the major portion of the circumference of the drums 35 are looped around rollers 24 on shaft 23, run over rollers 20 on shaft 16, over roller 36 on shaft 14, 35 over flanged rollers 37 carried by arms 38 loose on shaft 19, and over rollers 39 on shaft 15, and are finally looped around rollers 29 on shaft 28. From the hubs of arms 38 extend arms 40 on 40 which are hung weights 41 which keep the belts 34 at a constant tension as the thickness of the leaf-books B on drum 35 increases during the operation of the machine.

The drum 35 of the booking mechanism is 45 driven from shaft 28 by belts 34, the shaft 28 having a sprocket 42 driven by a chain 43 from a sprocket 44 on shaft 13 on which is mounted a pulley 45 driven by a belt 46. The chain 43 runs over idlers 47 and 48, the latter of which is 50 carried by an arm 49 pivoted to frame 10 and held in tension by a spring 50 to enable the chain to follow the movement of shaft 28 when the same is swung into the "open" position by turning handle 33. The two halves of the booking drum 55 35 are separated by flanges 51 between which the stems S of the leaves on the lead-in plate 27 are inserted by the operator.

For the purpose of supporting the endless band saws 57, there is provided across the side 60 frames 10, a bracket 52 which carries pairs of shafts 53 and 54 on which are mounted pulleys 55 and 56, respectively. These pulleys carrying the two endless band-saws 57 are driven in the 65 direction of the arrows by chains 58 running over sprockets 59 on shafts 60 driven by bevel gears 61 from the drum shaft 12 of the machine.

The band-saws 57 run over guide pulleys 62 and 63, the former of which is stationary while 70 the latter is mounted on a swingable arm 64 pivoted on bracket 52 and held by a spring 65. The tension of spring 65 holds the saws 57 in contact at the guide pulleys so that the saws are 75 yieldingly pressed against the stem S passing between them on plate 27 and thus closely follow

its contours along its length and yet yield to irregularities thereof.

In the operation of the machine, when inserting a stem, the operator depresses a foot-lever 66 connected by a rod 67 with a bell-crank lever 68 5 pivoted on bracket 52 and connected by a link 69 with the pulley-carrying end of arm 64, thereby overcoming the tension of spring 65 and causing the saws 57 to separate, although such an arrangement may be dispensed with as by pushing the stem down from above at the front where the belts converge in V formation. The entering stem rests on a roller 70 turnable on a shaft 71 supported in bearings 72 on plate 27, this roller supporting the stem against the downward 10 pressure of the moving banding saws. 15

The teeth of the band saws are set pointing or flaring away from each other and the stems on their inner sides. For this purpose they may be chamfered to a beveled or curved shape as shown at 57' in Fig. 3, thereby permitting the stem to enter smoothly between the saws bearing against it, and preventing the latter from cutting into the sides of the on-coming stem which may, owing to the pressure of spring 65, bulge beyond 20 the contacting sides of the saws. 25

The inclination of the inner faces of the sawing instrument relative to the stem in a direction flaring away from the stem surface toward the cutting edge is of importance because it enables the blades to hug the stem closely and thus obtain clean stemming from butt to tip while minimizing danger of cutting across the stem. This same feature makes possible pulling the stem through the stripping elements, with crooked 30 stems guiding themselves through said elements by contact with the inner surfaces of the element. 35

In connection with the operation of the illustrated stemming mechanism, it is noted that the outspread blade portions or laminae of the 40 leaves after being cut from the stem by the band saws pass between the book B on the drum 35 and the belts 34 and are gripped thereby so that the leaves after being manually started are pulled butt first through the saws. 45

What is claimed is:

1. In a tobacco stemming machine, the combination with a pair of flexible endless cutting members having adjacent cutting edges arranged to receive the stem of a tobacco leaf between them to cut the laminae from the stem, driving means for imparting cutting movement to said edges, a pressure element engaging at least one of said members, and means yieldingly urging said pressure element against said member toward the other member to cause said members to snugly engage the sides of stems of varying diameter, said endless members being arranged to cooperate against opposite sides of a tapering stem progressively from butt to tip for severing the laminae along their juncture with the stem, without waste, acting for that purpose as sensing means, regardless normally of the bodily displacement of the pressure element relatively to the axis of the stem. 65

2. In a tobacco stemming machine, the combination with a pair of flexible endless cutting members having adjacent cutting edges arranged to receive the stem of a tobacco leaf between them, means to support said cutting members in position to be brought together into contacting relation at a stripping station to cut the laminae from the stem, mechanism for yieldingly pressing said members against the sides of a leaf stem inserted therebetween butt first to cause said 70 75

members to snugly engage stems of varying diameter along the entire length of the stems, and driving means for imparting cutting movement to said edges.

- 5 3. In a tobacco stemming machine, the combination with a pair of flexible endless saws having adjacent cutting edges arranged to receive the stem of a tobacco leaf between them to cut the laminae from the stem, the faces of said saws, nearest the stem, adjoining the cutting edge of the saw, being inclined backwardly and outwardly with respect to the direction of movement of the stem, to provide a tapered entrance for the stem and to avoid cutting into the same, a 10 roller on which the entering stem is supported against the downward pressure of the saws as it passes therebetween, while free lateral flexure of the saws transversely to their broad faces is permitted, driving means for imparting cutting movement to said edges, and means behind said 15 members for drawing the leaves butt first through said members, whereby the trailing portion of the leaves will be left free in order that the same may be drawn through said members without 20 guiding.
- 25 4. In a tobacco stemming machine, the combination with a pair of flexible endless saws dis-

posed with their broad faces side by side and having adjacent cutting edges arranged to receive the stem of a tobacco leaf between them; means to support said saws in position to be brought into a position in which said faces approach each other with an interval less than that of the thinnest stem part to be stripped, mechanism for pressing said members against the sides of a leaf stem inserted therebetween butt first to cause said saws to snugly engage stems of varying diameter progressively along the entire length of the stems, with a pressure modulated exclusively in operation by the inherent flexibility and resilience of said saws, and driving means for imparting cutting movement to said edges, to cut 15 the laminae from the stem.

5 5. In a tobacco stemming machine, a pair of flat flexible band saws having their faces opposed and in position to engage a stem between them, said saws having arcuate cutting edges in continuance of said faces for cutting the laminae from a stem passing between said members, said adjacent arcuate cutting edges operating exclusively upon the portions of the laminae contiguous to the stem on each side, thereby to avoid 20 25 cutting into the stem.
